STUART PARMELEE MILLER, OF TENAFLY, NEW JERSEY, ASSIGNOR TO THE BARRETT COMPANY, OF NEW YORK, N. Y., A CORPORATION OF NEW JERSEY

APPARATUS FOR DISTILLATING TAR

Application filed June 3, 1927. Serial No. 196,269.

This invention relates to improvements in the distillation of tar, and particularly to the utilization of the heat available in the gases produced in coal-carbonization plants to distill tar and to produce clean oils and pitches by such distillation. The invention will be described especially with reference to its application to coke ovens.

Tar derived from various sources such as coke ovens, gas-house retorts, vertical retorts and water-gas sets, is shipped ordinarily from the plant where it is produced to a tar-distillation plant to be heated in stills for the purpose of driving off the more volatile constituents of the tar. Such distillation involves the provision of heat by the combustion of some suitable fuel and the consequent cost of the fuel as well as the expense of providing and maintaining the necessary distillation equipment.

It is the object of the present invention to provide for the distillation of tar at a coal-carbonization plant by utilizing the heat available in coal-distillation gases by spraying or otherwise bringing the tar into intimate contact with such gases while the latter are at high temperatures. The invention may be applied, for example, to by-product coke ovens which afford a source of large volumes of "foul" gases which escape from the ovens at temperatures of from 600° to 700° C. or higher.

The heat available in such gases produced by a coke-oven battery is many times the amount required to distill all of the tar and oils recovered from the battery. Consequently it is necessary to utilize only a portion of the gases produced by the battery to distill the tar and oils obtained therefrom. The heat can be utilized, likewise, to distill tar and oils from other sources such as gas-house retorts, etc. Provision may be made, therefore, in accordance with the present invention to utilize any desired quantity of the hot coke-oven gases for the purpose of distilling tar and oils as hereinbefore described. In large installations the heat from an entire battery can be used to distill tar from other batteries. Usually, however, it is sufficient to utilize the gases from a selected number

of the ovens, the gases from the remaining ovens being subjected in the usual manner to cooling in the collector main and in condensers provided for the purpose of separating tar and oils from the gases. The tar and oils thus recovered may be distilled by utilizing the heat in the gases from the remaining ovens of the battery to produce pitches of the desired character and clean distillates.

According to the present invention the hot gases from the selected ovens are subjected, preferably as soon as they are discharged, to intimate contact with tar or oil supplied thereto in a finely divided form for the purpose of reducing the temperature of the gases and of distilling the tar or oil. The gases are then utilized for the further distillation of the tar and oil in a tank still, for example, in which the tar or oil to be distilled is mingled intimately with the gases. The tar or oil and the pitch produced therefrom in the separate distillation operations may be recirculated for further distillation. The distillation can be controlled by varying the quantity of tar or oil supplied and the rate at which it is delivered to the gases. It may be controlled likewise by varying the character of the material supplied as, for example, by introducing regulated amounts of oil with the tar to be distilled or by supplying an aqueous cooling agent such as ammonia liquor either with the tar or oil or separately to the distillation apparatus. Regulation by the addition of ammonia liquor is particularly effective by reason of the greater specific and latent heats of water as compared with those of tar and oil.

Another feature of the present invention is the cleaning of the gases after utilization thereof by electrical precipitation. The gases which have been mingled intimately with the tar or oil to be distilled carry therefrom not only the vapors resulting from the distillation but also considerable quantities of tar in the form of globules or "tar fog". They carry in addition solid particles of coal, coke, etc., which may not have been removed completely by the scrubbing action of the tar in the distillation operations. The

solid and liquid particles and the "tar fog" can be removed effectively by passing the gases through an electrical precipitator of the type, for example, of the well known 5 Cottrell precipitator. The gases leaving the precipitator are free from solid particles and tarry materials, and upon cooling yield clean oils which can be utilized for various commercial purposes, particularly if the cooling 10 is effected in stages to separate the oil constituents in fractions.

In carrying out the invention the initial distillation is effected preferably in stills which are connected directly to the several 15 uptake pipes of the selected ovens. Such stills may comprise vertically disposed casings through which the gases pass upwardly in intimate contact with the tar or oil which is delivered in the form of a fine spray by 20 spray nozzles to which the tar or oil is supplied under a suitable pressure from a source thereof. In passing through the hot gases the tar or oil is distilled and the vapors join the gases and are carried away therewith, the 25 pitch or residue collecting in the bottom of each still and flowing to the larger still for further distillation by the gases.

The gases thus partially cooled and carrying the vapors resulting from the initial distillation are delivered preferably to a tank still which is disposed closely adjacent to the uptake stills and connected thereto so that the 30 gases from the several ovens are combined. In the latter still these gases are again intimately mingled with tar or oil to be distilled, the tar or oil being delivered preferably in the form of a fine spray by spray nozzles provided for that purpose. The 35 gases are thus further cooled and the heat thereof is utilized for the distillation of the tar or oil, the gases being thereby further enriched in oil vapors while the residue from the tar or oil accumulates in the still. Portions 40 of the pitch or residue may be withdrawn and recirculated and again introduced in the form of spray so as to mingle intimately with the hot gases for further distillation and the recovery of more of the volatile constituents therefrom.

55 The gases from the several uptake stills may be delivered thus through separate inlets to the still in which the heat of the gases is utilized or these gases can be combined and introduced thus to the still. The pitch produced in the individual uptake stills runs into the larger tank still in which it is subjected to further distillation, either with or without admixture with additional tar or pitch introduced into such tank still; and the pitch can 60 be recirculated to the uptake stills for further distillation therein. The cooling of the gases in the uptake stills avoids the separation of hard pitch and carbon in the connecting pipes and this result can be avoided also by suitable 65 regulation of the temperature as hereinbefore

indicated such as by the addition of oils or aqueous cooling agents either in the stills or in the connections leading thereto.

From the tank still the gases, which are considerably enriched in condensable constituents by the successive distillations and carry also solid particles and tar in the form of globules and "tar fog", are directed preferably into an electrical precipitator. The 70 cleaning of the gases by the electrical precipitator consists in passing the gases to be treated between electrodes whose difference in electrical potential is very great. It is best to use a rectified alternating current. The alternating current (the primary) is sent 75 through a step-up transformer to produce a high potential current (the secondary) which is then rectified to an intermittent uni-directional current, for example, by means of a rotary converter. The rectified current is delivered from the converter to the electrical precipitator at practically the potential at 80 which it leaves the transformer.

The electrical precipitator consists essentially of a group of vertical pipes with an axially located electrode in each which is supplied with the uni-directional high tension current, the pipes being connected to proper headers for the introduction and discharge of the gases. The pipes generally constitute 85 the positive electrodes, and the axially located wires or rods the negative electrodes. The size of the pipes may vary, but in general 90 pipes of less than six inches in diameter are not used. Electrical precipitators with pipes six 95 inches in diameter using secondary voltages from 35,000 to 50,000 volts are satisfactory for the purpose of this invention. It is generally best to operate with maximum potential difference (secondary current) between 100 the electrodes, this maximum being just below the break-down voltage at which arcing occurs.

The efficiency of the cleaning is dependent upon several variables. Satisfactory cleaning of the gas may be accomplished if the time of treatment is of the order of one second, although this time may be varied widely depending upon the extent to which it is desired to prevent contamination of the distilled products by tarry matter initially present in the hot gases. In working with six-inch tubes, for example, nine feet in length, it is possible to substantially free the gases from all solid and liquid constituents with a time 115 of treatment of from one and one-half to two seconds, that is to say, with a gas velocity of from six feet to 4.5 feet per second. This gives an efficiency of cleaning of approximately 99 per cent. A shorter treatment, for example, a treatment of from 0.5 to one second, that is to say, a velocity of from 120 eighteen to nine feet per second, may leave some tarry constituents in the gases.

The electrical precipitator should be dis- 130

posed preferably closely adjacent to the tank still so that the gases reach the precipitator still at relatively high temperature. The dew points of the gases for the several vaporized condensable constituents are lower than the boiling points of these constituents and by suitable regulation of the temperatures of distillation and of the subsequent cleaning of the gases in the electrical precipitator, it is possible to retain in the gases substantially all of the desired oil constituents in the vapor phase while the tarry constituents are present in the liquid phase and can be separated, therefore, from the gases in the electrical precipitator. The temperature of operation of the electrical precipitator should, therefore, be above the dew point of the most readily condensable oil constituent desired and below that at which the tarry constituents are condensed. With such operation the maximum quantity of the desired oil constituents can be recovered and these constituents will be free from contaminating tarry material. If some of the oil constituents are to be retained in the tar or pitch recovered, the temperature at which the electrical precipitator is operated will be modified accordingly so that this temperature is above the dew points of the gases for the constituents to be retained therein.

The gases and vapors leaving the electrical precipitator can be subjected to cooling for the purpose of condensing the volatile constituents therefrom. The cooling may be conducted so as to condense all or nearly all of the volatile constituents in a single operation, or it may be progressive so that the vapors are condensed in fractions, thus producing oils having distinct boiling ranges and other characteristics which are essential for the commercial application of such products. After such separation of the desired condensable constituents the gases may, if desired, be delivered to and mingled with the gases from the remaining ovens of the battery, for example, after the latter have been subjected to the usual primary treatment for the removal of tarry oils therein contained.

The invention as hereinbefore described embodies a single tank still with uptake stills connected to deliver hot coke-oven gases and partially distilled tar or oil thereto. It is possible, however, to use a plurality of tank stills with connected uptake stills and to circulate the tar to be distilled through such stills in series and to likewise convey the gases through the stills in various ways for the purpose of producing desirable pitch products and of enriching the gases in the vaporizable constituents of the tar. The tar to be distilled may be circulated through the tank stills and uptake stills in series or tar may be directed through the tank stills in series and other tar may be supplied to the uptake stills. The pitch products produced in the several stills may be withdrawn or they may be combined with other tar and redistilled in another still of the series. The gases may likewise be passed in succession through the tank stills either in the same direction or preferably counter-current to the flow of tar or pitch therethrough. Various such arrangements can be employed for the purpose of modifying the nature of the products. The temperature of the gases in the uptake stills is higher than the temperature in the tank stills and consequently the amount of distillation in the uptake stills per unit volume of gases is greater than in the tank stills and harder pitches may be produced therein. As an example of a practical arrangement, three tank stills may be employed, each being connected to a plurality of uptake stills so that the gases, after partial cooling in the uptake stills, are delivered to the tank stills. The gases may be withdrawn separately from the tank stills or circulated therethrough in succession and in either case the gases may be passed eventually through an electrical precipitator or precipitators and then through condensers to recover the condensable constituents. The tar to be distilled may be delivered first to the initial tank still and passed thence through the uptake stills connected therewith. The pitch produced in the uptake stills may be delivered then to the second tank still and conveyed thence through the uptake stills connected therewith. The pitch may be conducted then through the third tank still and thence through the uptake stills connected therewith from which it is withdrawn as a finished product. A portion of the pitch may be withdrawn from the tank stills and from the uptake stills so that pitches having various melting points and other characteristics can be recovered simultaneously from the system. The gases employed for distillation will carry oil vapors distilled from the tar and pitch and after separation of tarry constituents and solid particles in the electrical precipitators and the gases will upon cooling yield clean oils.

The application of the invention requires no substantial change or modification of the usual coke-oven recovery system except for the addition of the equipment required for distillation. Thus, the ovens of the battery may be connected through the usual uptake pipes to a collector main in which the gases may be cooled by sprays of ammonia liquor or ammonia liquor and tar. The gases may be conducted then through a cross-over main to the condensing system in which further cooling is effected. The tar and oils thus separated may be withdrawn and treated in decanters to separate the ammonia liquor which may be returned for further use as a cooling medium or subjected to treatment for the recovery of ammonia therefrom. The gases, after separation of the tar and

oils, may be delivered by the usual exhauster to the equipment provided for the separation of light oils and ammonia etc. The tar and oils may be subjected then to distillation either alone or with the addition of tars from other sources in accordance with the invention. The distillation equipment is disposed conveniently at the rear of the ovens and is connected to the selected ovens 10 of the battery through separate uptake pipes provided for that purpose. Valves may be disposed in the uptake pipes at the opposite ends of the ovens to permit direction of the gases either into the collector main or into 15 the distillation apparatus as may be desired. Thus, the coke-oven battery may be operated in the usual manner when no tar is to be distilled. When distillation is desired the 20 gases from the selected ovens will be diverted into the distillation apparatus while the gases from the remaining ovens are subjected in the normal manner to cooling for the purpose of separating tar and oils, therefrom.

25 The present invention is of more or less general application to the distillation of tar and oils and the recovery of desired residues therefrom. The invention involves the utilization of the hot gases from coal-carbonization plants for the distillation of tar and oil for the purpose of producing pitches and clean oils therefrom.

30 The invention will be further illustrated by the following more detailed description 35 taken with the accompanying drawings which show apparatus embodying the invention and adapted for the practice thereof, but it is intended and will be understood that the invention is not limited to the specific details of the apparatus as illustrated 40 in the drawings, in which

Fig. 1 is a plan view of a portion of a coke-oven plant illustrating the application of the invention thereto;

45 Fig. 2 is an enlarged view, partially in section, illustrating the stills and the electrical precipitator;

Fig. 3 is a detail in section of the electrical precipitator;

50 Fig. 4 is a plan view of a portion of the coke-oven plant illustrating a slightly different arrangement of the apparatus;

Fig. 5 is an enlarged sectional view of the uptake stills connected to a collector 55 main from which the gases are delivered to the second still; and

Fig. 6 illustrates diagrammatically an arrangement of uptake stills and tank stills in connection with a coke-oven battery to 60 permit continuous counter-current distillation of tar and pitch.

Referring to the drawings, 5 indicates a battery of coke ovens in which the individual ovens are connected by uptake pipes and 65 goose-necks 6 to a collector main 7 having

a centre box 8 from which a cross-over main 9 conveys the gases and vapors to the condensing system. The tar or other liquids which accumulate in the centre box can be withdrawn through a pipe 10. The tar which separates in the cross-over main 9 is delivered by a pipe 11 to a decanter 12 in which it is separated from ammonia liquor. The tar can be delivered through a pipe 13 to a storage tank 14 and the ammonia liquor can be discharged through a pipe 15 to a storage tank 16. The gases pass through condensers 17 in which they are further cooled to separate oils. The latter are delivered through a pipe 18 to a decanter 19. The separated oils pass through pipes 20 and 13 to the storage tank 14 or to separate storage tank 14' through line 13'. The ammonia liquor which separates in the decanter 19 is delivered through pipes 21 and 15 to the storage tank 16. Liquids which may separate in the pipe 22 leading from the condensers are delivered by a pipe 23 to decanter 19 in which ammonia liquor is separated from the oil. The gases are delivered to an exhauster 27 which maintains the pressure balance in the system and pass thence to the usual equipment (not shown) for the separation of light oils, ammonia etc. The ammonia liquor may be delivered from the tank 16 through a pump 28 and pipe 29 to spray nozzles 30 and 31 in the collector main and the goose necks leading thereto for the purpose of cooling the gases as hereinbefore described. The structure as indicated is typical of a by-product recovery system employed in connection with coke-ovens. It may be modified in accordance with the customary or any desired practice.

To facilitate the practice of the invention selected ovens of the battery may be provided with uptake pipes 32 which, as indicated in Fig. 2, are connected directly to uptake stills 33, the latter comprising casings into which the tar to be distilled is introduced through spray nozzles 34 which are supplied by pipes 35 from any suitable source of tar or oil to be distilled. The tar or oil which is introduced in the form of a fine spray passes downwardly in contact with the upwardly moving streams of hot coke-oven gases and is subjected thereby to distillation to separate the more readily vaporizable constituents. The pitch produced can be delivered through a pipe 35' to a still 36 to which a number of uptake stills are connected by pipes 37 having valves 38 therein to permit control of the operation. The tar or oil to be distilled in the uptake stills may be withdrawn through a pump 39, for example, from the still 36 and delivered to the pipes 35 for recirculation through the uptake stills.

The tar or oil to be distilled may be supplied from the tanks 14 or 14' by a pump 40 and delivered through a pipe 41 to a plurality of

- spray nozzles 42 within the still. The tar or oil is atomized by the spray nozzles and is introduced thus in finely divided form to the stream of hot gases passing through the still. 5 Distillation of the tar or oil is thus effected and the pitch produced accumulates in the still and may be withdrawn through a pipe 43. A portion of the pitch may be recirculated through a pipe 44, pump 45 and pipe 10 46. Tar or oil from other sources may be introduced to the system through a pipe 47 and caused to circulate therein in the manner described. 15 The gases, after passing through the still 36, escape through an outlet 48 to an electrical precipitator comprising a casing 49 having a plurality of tubes 50 therein supported in heads 51 so that the gases, after passing a baffle 52, are conveyed through the tubes to 20 an outlet 53. A plurality of electrodes 54 are supported from a bus-bar 55 at the top of the casing 49, and extend through the tubes. The bus-bar 55 passes into casings 56 at the sides of the precipitator and is supported upon insulators 57 therein. Current is supplied through a conductor 58 from any suitable source of uni-directional high tension current. The electrodes 54 are normally negative and the casing 49 with the tubes 25 therein is grounded and connected to the positive side of the circuit. The arrangement of conductors and of the circuits whereby current is supplied to the precipitator forms no part of the present invention. 30 In passing through the tubes of the precipitator the gases carrying entrained tar in the form of globules or "tar fog," together with solid material such as carbon in finely divided form, are subjected to the electrical discharge which causes the suspended particles to separate from the gases. The separated liquid, together with the solid particles, run down the inner walls of the tubes into the chamber at the bottom of the precipitator 35 and may be withdrawn through a pipe 59 and delivered to any suitable storage receptacle. The gases which escape from the precipitator through the outlet 53 are delivered to a plurality of condensers 60 arranged in series. In these condensers the gases are cooled in stages to effect the condensation of desired fractions of the oils. These fractions are delivered through pipes 61 to storage receptacles 62. The gases may be delivered then 40 by an exhauster 63 through a pipe 64 to the exhauster 27 and mingled there with the gases from the remaining ovens of the battery. The pitch which leaves the still 36 through 45 the pipe 43 may be accumulated in a tank 65, and similarly pitch which is withdrawn from the electrical precipitator can be accumulated in the tank 66, although ordinarily this pitch will be returned as made to the still 36. 50 Referring to Figs. 4 and 5 of the drawings, the structure is substantially identical with that previously described except for the provision of a short collector main 67 to which the uptake pipes 68 and stills 69 are connected. The gases which have been partially cooled by intimate contact with tar or oil in the stills 69 are delivered to the short collector main 67 and may be further cooled therein if desired by the application of sprays of the tar or oil or of an aqueous cooling agent such as ammonia liquor. The gases are delivered through a pipe 70 to a still 71 which may be substantially identical with the still 36 previously described. Pitch accumulated in the still 71 may be recirculated through a pump 72 and pipe 73 to the uptake stills 69, and the pitch produced therein can be returned through a pipe 74 to the still 71. Similarly, the pitch may be recirculated through a pump 75 and pipe 76 for further distillation in the still 71. The pitch produced in the still 71 may be withdrawn as desired through a pipe 77 and accumulated in a tank 78. 70 The gases pass from the still 71 through a pipe 79 to an electrical precipitator 80 which may be identical with the precipitator 49 as hereinbefore described. The pitch which separates from the gas in the precipitator may be withdrawn through a pipe 81 and delivered to a tank 82 or it may be returned to the still 71. The clean gases pass through a pipe 83 to condensers or fractionators 84 arranged in series to condense desired oil constituents from the gases. These oils may be delivered through pipes 85 to tanks 86. The gases are then delivered through an exhauster 87 and pipe 88 to the exhauster 27 where the gases are mingled with gases from the remaining ovens of the battery. 80 Referring to Fig. 6 of the drawings, three tank stills 90, 91 and 92 are each connected by goose-necks 93 to groups of uptake stills 94, 95 and 96 which receive the hot coke-oven gases directly from the ovens. The tar to be distilled may be introduced to the tank still 90 through a pipe 97 and suitable spray nozzles in the still so that the tar is intimately mingled with the hot gases delivered thereto through the goose-necks 93 and also if desired from the succeeding tank stills 91 and 92. The partially distilled tar is withdrawn through a pump 98 and is delivered by a pipe 99 to the uptake stills 94 and is introduced thereto in a finely divided condition by spray nozzles provided for that purpose. The tar is thus intimately mingled with the hot gases in the uptake stills and is subjected to further distillation therein. The pitch is withdrawn through a pipe 100 and delivered to the tank still 91 wherein it is mingled intimately with hot gases from the uptake stills 95 and if desired with gases from the tank still 92. The pitch is withdrawn by a pump 101 and is delivered by a pipe 102 to the up- 100 105 110 115 120 125 130

take stills 95 and is subjected to further distillation therein by intimate contact with the hot coke-oven gases. It is withdrawn through a pipe 103 and is delivered to the 5 tank still 92 for further distillation with hot gases from the uptake stills 96. The pitch passes through a pump 104 and pipe 105 to the uptake stills 96, being subjected therein to final distillation with the hot coke-oven 10 gases. It is withdrawn through a pipe 106. Pitch products may be withdrawn also through pipes 107, 108, 109, 110 and 111. It will be understood that in each still intimate 15 contact between the hot coke-oven gases and the tar or pitch to be distilled is accomplished either by spraying the tar or pitch into the hot gases or by suitable agitation in the still to disseminate the tar or pitch in finely divided form through the gases.

20 The hot gases from the tank still 92 may be delivered through a pipe 112 to the tank still 91 for utilization therein in distilling tar or pitch and similarly the gases from the tank still 91 may be delivered through a 25 pipe 113 to the tank still 90. The gases may, however, if desired, be withdrawn from each of the tank stills for treatment in electrical precipitators 114, 115 and 116, for the purpose of separating tarry and solid constituents from the gases. The clean gases 30 may be cooled then in suitable condensers 117, 118 and 119 for the purpose of recovering the condensable constituents. If the gases are conducted in succession through the several 35 tank stills a single electrical precipitator 114 will serve for the cleaning of the gases which may be conveyed then through the condenser, 117. If the gases from the several tank stills are separately treated the condensate can be 40 withdrawn through pipes 120, 121 and 122, and the gases may be conducted through the condensers in series through pipes 123 and 124. It will be understood that suitable valves are provided in the several pipe lines 45 to permit the direction of the tar and pitch and of the gases through the apparatus and the withdrawal of different products at several points therefrom, and that these valves will be manipulated to permit the 50 treatment of the tar or pitch in accordance with the products which are to be recovered. By modifying the operation as hereinbefore suggested, pitches having different melting points and other characteristics can be with- 55 drawn and clean oils can be recovered. The gases after separation of the oils therefrom in the condenser may be subjected in the usual manner to further treatment for the recovery of ammonia, light oils, etc., there- 60 from.

Several embodiments of the invention involving the principles set forth have been described in more or less detail in order that the application of these principles may be 65 clearly understood. It will be understood

that the several examples are illustrative and that various changes may be made in the form and arrangement of the apparatus employed and in the steps utilized without departing from the invention or sacrificing any 70 of the advantages thereof.

I claim:—

In combination with a coke oven a plurality of stills, means for passing gases from each of a plurality of the ovens to each of the 75 stills, and means for introducing tar into each of the stills, and means for withdrawing distillation residue therefrom, a large still, means for introducing the residue into the large still, means for passing gases from 80 each of the plurality of stills to the large still and means for bringing the residue into direct contact with the gases therein in the form of a spray.

In testimony whereof I affix my signature. 85
